United States Patent Office.

A. E. PECK, OF BROOKLYN, NEW YORK.

Letters Patent No. 96,143, dated October 26, 1869.

FIRE-CRACKER HOLDER.

The Schedule referred to in these Letters Patent and making part of the same.

To all whom it may concern:

Be it known that I, A. E. PECK, M. D., of Brooklyn, in the county of Kings, and State of New York, have invented a new improved Breech-Loading Fire-Cracker Holder; and I do hereby declare that the following is a full, clear, and exact description thereof, which will enable others skilled in the art to make and use the same, reference being had to the accompanying drawings, forming part of this specification, in which—

Figure 1 is a side view of my improved holder, made in the form of a pistol.

Figure 2 is a longitudinal section of the same, made in the form of a cannon.

Similar letters of reference indicate corresponding parts.

My invention has for its object to furnish an improved holder for fire-crackers, while being discharged, in such a way that the cracker may be discharged or exploded with perfect safety, while projecting the shell of the fire-cracker from the muzzle of the holder, and which shall at the same time be breech-loading; and

It consists in the breech-loading fire-cracker holder, constructed as hereinafter more fully described.

The barrel of the holder is made in two parts, A and B, the line of division passing through the touch-hole, and dividing the barrel into two nearly equal parts.

The parts A and B of the barrel of the holder are kept in proper position by a rubber band, C, passing around the two parts of the holder opposite or nearly opposite the middle part of the fire-cracker, when inserted in the holder.

In placing the fire-cracker in the holder, the rear

end of the shorter or upper part A of the holder is raised sufficiently to allow the fire-cracker to be inserted, the fuse of the fire-cracker passing through the groove in the breech of the part B, which, in connection with the corresponding groove in the rear end of the part A, forms the touch or fuse-hole.

By this construction, when the fire-cracker is discharged or exploded, the band C gives, allowing the developed gases to escape, in part, through the opening between the two parts A and B, the shell of the fire-cracker being projected from the muzzle of the holder with sufficient force to carry it to a considerable distance, if unobstructed, but not with sufficient force to harm any one if he should be accidentally hit. In fact, the projected shell may be caught in the hand without harm, as it issues from the muzzle of the holder.

The stock or handle of the holder A B C may be made to resemble a pistol, as shown in fig. 1, or a cannon, as shown in fig. 2, or in any other convenient form.

Having thus described my invention, I claim as new, and desire to secure by Letters Patent—

An improved cracker-holder, formed in two sections, A B, substantially as specified.

The above specification of my invention signed by me, this 24th day of May, 1869.

A. E. PECK, M. D.
